Des. 403

Ruben I Blanchard of Albany N.Y.
Letters Patent dated July 29, 1857
(assigned to Learned & Thatcher)

No 403

Des. 493

The schedule referred to in these letters, and making part of the same
 Patent

To all whom it may concern

Be it known that I Reuben J. Blanchard of the city and county
 of Albany in the State of Newyork have invented or produced a new
 and original design for cast iron stove plates consisting of ornaments
 to be cast thereon, and I do declare that the following is a full and
 exact description of the same, reference being had to the annexed
 drawings which form part of this specification

Figure 1 represents one half of the end plate of the stove
 Figure 2 represents one half of the front plate of the stove and
 Figure 3 represents one quarter of the top plate of the stove. The other
 parts of these plates are similar and corresponding to those represented
 in the drawings

The ornament on the upper part of the front end and
 plate consists of looped up drapery and tassels, there is a vine like
 ornament on a part of the front plate, but most of the decoration
 on the plates is a kind of bat wing ornament as seen in the drawings.
 The ornament is in relief

What I claim as my invention and desire to secure by letters patent is
 the ornamental design above described and delineated in the annexed
 drawings as an ornament for the plates of cast iron stoves

Dated July 8 1851.
